J. Abercrombie & Co.
Atty's.

UNITED STATES PATENT OFFICE.

LOUIS E. FRANKE, OF WASHINGTON, DISTRICT OF COLUMBIA.

WATER-WHEEL.

1,391,730.

Specification of Letters Patent. Patented Sept. 27, 1921.

Application filed May 11, 1917. Serial No. 167,885.

To all whom it may concern:

Be it known that I, LOUIS E. FRANKE, a citizen of the United States, residing at Washington, District of Columbia, have invented new and useful Improvements in Water-Wheels, of which the following is a specification.

This invention relates to water wheels for use in relatively small or sluggish streams, which ordinarily do not have flow or fall enough to operate a water wheel of usual construction with sufficient force to operate a generator.

The object of the invention is to increase the pressure of the water upon the main wheel so that streams now unavailable for such plants may be used.

With this object in view, the invention consists in the arrangement, construction and combination of parts hereinafter described and particularly pointed out in the claims, it being understood that I do not intend to limit myself to the details of construction.

The invention is illustrated in the accompanying drawings, in which,

Figure 1 is a plan view of the complete device with parts broken away.

Fig. 2 is a side elevation also with parts broken away.

Figs. 3 and 4 show side views of modified forms of both impeller wheel and stop, and,

Figs. 5 and 6 show further modifications of details.

In the drawings the numeral 11 indicates a trough or box, through which water of the stream is adapted to pass in the direction of the arrow and in which is located a main power wheel 12 equipped with curved blades 13, held in spaced relation by the fellies 14. 15 indicates a driving pulley.

In advance of the wheel 12 is journaled the water impeller wheel 16 forming the basis of this invention and the forward end 45 of the box or housing 11 is provided with a flume 17, preferably having curved and tapered side walls 18. 19 indicates a shelter for a generator 20, which generator has a pulley 21 driven by a belt 22 or other device 50 from the driving pulley 15. B indicates a fan on the generator shaft for circulating the air in the shelter to prevent condensation upon the generator.

The impeller wheel 16, shown in Fig. 2, 55 is provided with a hub part 24 to which are connected blades 25 by means of spring

hinges 26. Pivoted centrally of the front edge of each blade is a roller 27 and a cup-shaped guard 28 is provided back of each roller, so that no effective area of the blades 60 will be lost.

A pivoted lever 29 is carried by the floor of the housing 11, so located as to engage the rollers 27, as shown in Fig. 2. This lever is upwardly pressed by a comparatively strong spring 30 and upward movement of the lever may be adjustably limited by the screw 31.

In operation the flow of the water rotates the impeller wheel 16 until a blade 25 by 70 means of its roller 27 engages the lever 29, whereupon it is moved backward upon its hinges 26 or retarded as shown in Fig. 3, which retardation compresses the springs 75 of the spring hinges 26. Continued rotation of the wheel will cause the retarded blade to slip off the lever 29, so that it slaps or impels the water sharply upon the blades of the main wheel, due to the release of the tension of the springs in the hinges 26. Thus 80 increased pressure is brought to bear upon the main wheel 12. Raising or lowering the lever 29 will naturally vary the retardation of the blades and consequently vary the strength of the blow struck the water by the 85 blade for the compression of the springs of the hinges will be changed accordingly.

In Fig. 3 instead of the spring hinges of Fig. 2 I may use ordinary hinges 32 but have springs 33 extend between the blades 90 as illustrated. With this form I may use the retarding lever 29 or I may substitute for it the pin 34 carried in a socket 35, provided with a set screw 36 for adjusting the height of the pin vertically to adjust the 95 retardation of the blades.

In Fig. 4 I may combine the use of both spring hinges 37 and springs 38 between the blades. Instead of rollers on the blades I may provide curved shoes 39, as shown and instead of the retarding means so far described I may use a pivoted pin 40 with springs 41 and 42 for maintaining it normally upright, it being understood that the spring 41 is sufficiently strong to overcome 105 the springs 38 and 37.

The operation of the modified forms of Figs. 3 and 4 is the same as the form of Fig. 2 and therefore need not be reiterated.

In Figs. 5 and 6 the retarding elements 110 are placed at the sides of the blades. The rollers 43 instead of being on the blades are

- supported from the floor of the casing 11. The blades carrying two sets of superposed lugs 44 are adapted to slidably carry the stem 45 of a head 46 having a tapered face. 5 A nut 46 is threaded on the stem 45 between the lugs 44, whereby rotation thereof will raise and lower the head 46, which is adapted to engage the roller 43. Rotation of the impeller wheel causes the heads 46 10 to engage the rollers 43, whereby the blade is retarded by means of rotating about its spring hinges until the heads can slip over the rollers and strike the desired blow. Adjustment of the heads vertically varies this 15 blow.
- What I claim is:
1. In combination with a water wheel, an impeller wheel co-acting therewith, said im-

peller having spring pressed hinged blades, and a stop in the path of said blades intermittently obstructing the movement of said impeller. 20

2. The combination of claim 1 with anti-friction elements on the engaging parts of the blades and stop. 25

3. In combination with a water wheel, an impeller wheel co-acting therewith, said impeller having spring pressed hinged blades, a stop in the path of said blades, and means extending from the blades for engaging the stop whereby the impeller is intermittently obstructed in its movement. 30

4. The combination of claim 3 with the addition of means for adjusting the stop and means with relation to each other. 35

LOUIS E. FRANKE.
